UNITED STATES PATENT OFFICE.

EUGÈNE SCHNEIDER, OF LE CREUZOT, FRANCE.

APPARATUS FOR STABILIZING THE POSITION OF SUBMERGED FLOATING MINES.

1,229,661.

Specification of Letters Patent. Patented June 12, 1917.

Application filed February 11, 1916. Serial No. 77,710.

To all whom it may concern:

Be it known that I, EUGÈNE SCHNEIDER, a citizen of the Republic of France, residing at Le Creuzot, France, have invented a new and useful Improvement in or Relating to Apparatus for Stabilizing the Position of Submerged Floating Mines, which is fully set forth in the following specification.

10 This invention has for its object to provide improved apparatus for stabilizing the position of submerged floating mines.

It is well known that the flow of the water displaced by the hull of a ship is apt to 15 have a deflecting effect upon submerged floating mines that may be situated in the path of the said hull, to the extent of shifting the mines to such a distance as to prevent them from coming into contact with 20 the said ship.

The stabilizing apparatus hitherto proposed for the purpose of opposing such deflections of the mines act solely by their mass or their shape.

25 Consequently they increase unduly the weight or the bulk of the whole arrangement without however achieving the object in view inasmuch as they prevent only incompletely the shifting of the position of 30 the mine in vertical and horizontal directions, and also they do not assure the prompt return of the mine into a useful position.

To facilitate the understanding of the nature of the present invention reference 35 is now to be had to the accompanying drawings.

In these drawings:—

Figure 1 illustrates in a diagrammatic manner a submerged floating mine of any 40 known type fitted with a stabilizing apparatus of the usual kind, and shows the position which it tends to assume;

Fig. 2 illustrates in diagram, in two positions of operation, a submerged floating 45 mine fitted with an apparatus according to this invention;

Figs. 3 to 5 are views illustrating a practical construction of the invention; Fig. 3 being a sectional elevation of the whole arrangement, showing the parts in the positions which they occupy before the mine 50 is sunk in place; Fig. 4 an elevation of the mine sunk in place, and Fig. 5 a horizontal section of the stabilizing apparatus;

Fig. 6 is a view of a modified form of 55 the stabilizer;

Figs. 7 and 8 are horizontal sections showing the parts of the modified stabilizer in two different positions.

Referring to Fig. 1, the full lines show 60 a mine A connected by a connection B to a float C and also connected by a connection D to a stabilizer E. Assuming that the whole arrangement A—B—C—D—E is 65 acted upon by the flow of the water displaced by the hull of a ship, it will be shifted from the position shown in full lines into the position indicated by dash and dot lines A¹—B¹—C¹—D¹—E¹, and it will then have a tendency, after the action 70 of the flow of water has ceased, to take up a position of equilibrium such as that indicated by dotted lines A²—B²—C²—D²—E².

It will be perceived that this return into the position of equilibrium is due almost 75 entirely to the action of the weight of the stabilizer E. Now the latter by its shape offers as much resistance to descent as to ascent and therefore the return will be accomplished slowly. Moreover, if the mine 80 A has a negative buoyancy, the stabilizer E will exert upon it only a very slight returning force or it may be none at all, depending on the relation between the weight and the shapes of the mine with its 85 float and the stabilizer, so that in the end the whole arrangement of the mine will return only with exceeding slowness, or perhaps not at all, into a position where it can become again dangerous to the ship. 90

If on the contrary the mine A has a positive buoyancy it will tend to rise to the surface and will therefore oppose a resistance to the returning force of the weight of the stabilizer E. In any case the whole arrangement when shifted by the flow of water will be returned incompletely and too slowly into an efficient position.

The present invention has now for its 100 object to provide improved stabilizing apparatus which will do away with all the above stated drawbacks. It consists essentially in rendering the whole arrangement deformable in such a manner as to enable the mine to have a great facility of 105 descent into the desired position of immersion, while on the contrary rendering it difficult for the mine to become shifted

from this position. In carrying this invention into effect the deformability of the whole arrangement is due to the use of a stabilizer provided with bellows or valves 5 or clacks which become inoperative during the descent of the apparatus but become operative during the ascent of the same, and also of elastic means arranged in the connection between the stabilizer and the 10 mine and also in the connection between the mine and the float.

In the diagrammatic Fig. 2, A, C, E are respectively the mine, the float and the stabilizer. The latter is provided with clacks 15 F and G adapted to fold back against the outer and inner sides of the stabilizer E, and also to take up a horizontal position. It will be at once perceived that in the descending movement the clacks do not offer 20 any resistance, whereas on the contrary in the ascending movement they offer resistance with their whole surface.

The connections D and B which connect the mine A to the stabilizer E and to the 25 float C, comprise elastic devices d b respectively which consist of springs (rubber bands or the like, metal springs, or it may be compressible bodies containing air).

When such an arrangement occupying the 30 position shown in full lines tends to be shifted by the action of the flow of the water displaced by the hull of a ship, it will be readily understood that the stabilizer that is situated at a depth out of range of the action of the flow of the displaced water will offer to the shifting action of said flow a resistance that is increased by the whole resistance of the horizontally extended clacks F and G.

40 On the other hand the stabilizer will have less tendency to be pulled away by the mine owing to the fact that the greater part of the pulling away strain exerted by the latter is absorbed by the elastic connection d. 45 Similarly, the entire pulling strain between C and A is mainly absorbed by the elastic connection b. In fact it can be assumed that the whole arrangement will have a tendency to take up the position shown in dotted lines, 50 the stabilizer E remaining practically in its initial position.

When the action of the flow of water ceases to make itself felt, the elastic connections b¹ d¹ will contract, and the whole arrangement will tend to return rapidly into its initial position.

In practice the stabilizer and the deformable connections may have various constructional forms.

60 In the construction shown in Figs. 3 to 5, the stabilizer comprises a framework made of sheet metal or formed of uprights to which canvas sides may be attached. This framework (metal sheets e and angles e¹) 65 is left on the mine A up to the moment of

sinking, while the bottom of the framework is closed by the clacks G which bear upon a crossbar g and are adapted to rise and bear against the inside faces of two of the sides of the framework. F are clacks which are pivoted in such a manner as to be kept in their raised positions, bearing against the outer sides of the framework, by pins f that are suspended by cords f¹ from the mine A. The extent of the downward movement of these clacks is limited by means of cords f² attached at one end to the said clacks and at their other ends to the stabilizer.

The elastic connections b and d are assumed to consist of straps or bands of rubber. These connections may be arranged as shown in the drawings between the float and the cable B, and between the mine A and the cable D. They may however be arranged at any other points in the length of the line that connects the devices C and A and A and E together. They may also be divided up into a plurality of elastic connections separated from one another in the length of the line by non-elastic sections.

In sinking the mine the float C which up till then has been hooked to the mine A (as shown in Fig. 3) is unhooked and then the whole arrangement is thrown into the sea. 95 The stabilizer E and the mine A sink by reason of their negative buoyancy, and the several elements automatically take up their respective positions shown in Fig. 4.

In the modification illustrated in Figs. 6, 7 and 8, the stabilizer is made up of metal sheets e arranged in the form of a cross coming to a point at its lower part. To the edges of this lower part there are attached flexible diaphragms F which in the descent of the stabilizer fold back against the framework of the stabilizer as shown in Fig. 8. The rising of the stabilizer is on the contrary opposed by the resistance offered by the pockets formed by the metal sheets and the inner sides of the diaphragms, which diaphragms then extend to the positions shown in Fig. 7.

The clacks or the folding flexible diaphragms which form pockets and hinder the ascent of the whole arrangement may, instead of being provided only in a separate stabilizer, be provided also on the mine and thus enable the latter to operate as a stabilizer with respect to the float.

Having now described my invention what I claim as new and desire to secure by Letters Patent is:—

1. In a submarine mine, in combination with the mine proper and its stabilizer, connections therebetween comprising an elastic medium.

2. In a submarine mine, in combination with the mine proper and its float, connections therebetween comprising an elastic medium.

3. In a submarine mine, in combination with the mine proper, its stabilizer and its float, connections between said mine and said stabilizer and float each comprising an elastic medium.
- 5 4. In a submarine mine, in combination with the mine proper, a stabilizer connected thereto comprising a frame and means connected therewith adapted to take up a position contiguous to said frame during descent of the stabilizer and adapted to take up a position in expanded relation to said frame during ascent of the stabilizer.
- 10 5. In a submarine mine, in combination with the mine proper, a stabilizer connected thereto comprising a frame and means movably connected therewith and adapted to move to a position adjacent said frame during descent of the stabilizer and adapted to move to a position projecting from said frame during ascent of the stabilizer.
- 15 6. In a submarine mine, in combination with the mine proper, a stabilizer connected thereto comprising a frame and means adapted to fold inwardly during descent of the stabilizer and to unfold outwardly during ascent of the stabilizer.
- 20 7. In a submarine mine, in combination with the mine proper, a stabilizer connected thereto comprising a frame and clacks adapted to move to a position adjacent the frame during descent of the stabilizer and adapted to move to a position projecting from the frame during ascent of the stabilizer.
- 25 8. In a submarine mine, in combination with the mine proper, a stabilizer connected thereto comprising a polygonal frame and clacks hinged thereto to unfold downwardly.
- 40 9. In a submarine mine, in combination with the mine proper, a stabilizer connected thereto comprising a polygonal frame and clacks hinged to its outer faces to unfold outwardly.
- 45 10. In a submarine mine, in combination with the mine proper, a stabilizer connected thereto comprising a polygonal frame and clacks hinged to inner faces thereof to fold inwardly.
- 50 11. In a submarine mine, in combination with the mine proper, a stabilizer connected thereto comprising a polygonal frame and clacks hinged to inner and outer faces thereof to unfold downwardly into angular relation to said frame.
- 55 12. In a submarine mine, in combination with the mine proper, a stabilizer connected thereto comprising a polygonal frame and clacks hinged thereto to unfold downwardly, and means to limit the downward movement of said clacks.
- 60 13. In a submarine mine, in combination with the mine proper, a stabilizer of box-like structure connected to said mine and adapted to receive the lower end thereof.
14. In a submarine mine, in combination with the mine proper, a stabilizer of box-like structure connected to said mine and adapted to receive the lower end thereof, said stabilizer comprising means adapted to fold upward during descent thereof and to unfold downward during ascent thereof.
- 70 15. In a submarine mine, in combination with the mine proper, a stabilizer of box-like structure connected to said mine and adapted to receive the lower end thereof, said stabilizer comprising means adapted to fold upward during descent thereof and to unfold downward during ascent thereof, and means for retaining said last-named means in folded relation to the stabilizer, said retaining means being rendered inoperative by separation of said mine and stabilizer.
- 75 16. In a submarine mine, in combination with the mine proper, a stabilizer of box-like structure connected to said mine and adapted to receive the lower end thereof, said stabilizer comprising means adapted to move to a position adjacent thereto during descent of the stabilizer and adapted to move to a position projecting therefrom during ascent of the stabilizer.
- 80 17. In a submarine mine, in combination with the mine proper, a stabilizer connected thereto comprising a frame and means adapted to fold upwardly during descent of the stabilizer and to unfold downwardly during ascent of the stabilizer.
- 85 18. In a submarine mine, in combination with the mine proper, a stabilizer, and connections comprising an elastic medium between said mine and stabilizer, said stabilizer comprising a frame and means connected therewith adapted to move to a position adjacent said frame during descent of the stabilizer and adapted to move to a position projecting from said frame during ascent of the stabilizer.
- 90 19. In a submarine mine, in combination with the mine proper, a stabilizer, and connections comprising an elastic medium between said mine and stabilizer, said stabilizer comprising a frame and means connected therewith adapted to fold upwardly during descent of the stabilizer and adapted to unfold downwardly during ascent of the stabilizer.
- 95 20. In a submarine mine, in combination with the mine proper, a stabilizer, and connections comprising an elastic medium between said mine and stabilizer, said stabilizer comprising a frame and means connected therewith adapted to fold inwardly during descent of the stabilizer and adapted to unfold outwardly during ascent of the stabilizer.
- 100 21. In a submarine mine, in combination with the mine proper, a stabilizer comprising means which move to a position offering substantially no resistance to the passage of
- 110
- 115
- 120
- 125
- 130

the stabilizer downwardly through the water but which automatically move to a position offering large resistance to any force tending to raise the stabilizer through the water, whereby the mine is maintained in its predetermined position.

In testimony whereof I have signed this

specification in the presence of two subscribing witnesses.
